(57) **CLAIM**

The ornamental design for a bassinet, as shown and described.

DESCRIPTION

FIG. 1 is a perspective view of the design for a bassinet of the present invention.

FIG. 2 is a left elevational view of the bassinet of FIG. 1.

FIG. 3 is a right elevational view of the bassinet of FIG. 1.

FIG. 4 is a bottom elevational view of the bassinet of FIG. 1.

FIG. 5 is a top elevational view of the bassinet of FIG. 1.

FIG. 6 is a front elevational view of the bassinet of FIG. 1; and,

FIG. 7 is a back elevational view of the bassinet of FIG. 1.

The broken lines illustrated in the drawings form no part of the design.
